METHOD OF DRYING PHOTOGRAPHIC MATERIAL

Cornelis Johannes Dippel, Jan Anthony Lely, and Johannes Aloysius Maria Dikhoff, Eindhoven, Netherlands, assignors to Hartford National Bank and Trust Company, Hartford, Conn., as trustee.

Application May 19, 1947, Serial No. 748,974
In the Netherlands June 1, 1946

4 Claims. (Cl. 34—1)

1

It is known to manufacture photographic material by sensitizing paper, regenerated cellulose and the like by treating it with an aqueous solution of a light-sensitive nitrogen compound, for example, a diazonium compound, and by subsequent drying by passing the sensitized material through a heated chamber.

The manufacture of such photographic material is cheap, since both the sensitizing and the drying operation can be effected in a very simple manner. This is of importance with a view to the manufacture of copying material for image films, sound films, and combined image-and-sound films.

The invention has for its object a further simplification of the manufacture. It permits the drying process to be effected very rapidly by means of apparatus which occupy only little space. It is known to effect the sensitization rapidly and by means of compact apparatus, the speed of manufacture of the said photographic material and the size of the apparatus required therefor being fundamentally determined by the rate of drying and the size of the drying chamber. By making use of the invention, it is possible to carry out the whole process rapidly and by means of apparatus occupying little space.

According to the invention the sensitized material is dried by heating it in a high frequency electric field. While passing a stream of gas over the photographic material in order to carry away any evolved water vapour, the material is treated in an electric field having such a frequency and strength that, on an average, at least 15 percent. by volume of water is expelled per second. This means that in each cubic centimetre of the material an energy of at least about 80 calories per second is produced. A value of 15 percent. by volume of water is to be understood to mean 15 cc.'s of water per 100 cc.'s of dry material.

If a heating method according to the invention is used for a film strip consisting of regenerated cellulose having a thickness of 40μ , which contains 5 mgs. of water per sq. c. of its surface after sensitization, it is possible to dry the film strip in approximately 6 seconds. If the film strip is passed through an electric field which extends over a length of 45 cms., the speed may consequently be about 5 ms. per minute. According to the invention, it is even possible to raise the speed of drying to a degree such that 30 percent. by volume of water is expelled per second.

It is surprising that it has been found to be possible to heat the photographic material to such

2

a high degree without jeopardizing the sensitized compound, which is very remarkable, since light-sensitive nitrogen compounds, such as diazonium compounds, azides and the like, readily decompose on being heated and would disintegrate for the greater part at such an intensive heat supply in a drying chamber operated, for example, by means of hot air. Furthermore it should be considered that, according to the invention, heat is developed within the material, so that the interior of the material is warmer than its surface. In the case of external heating, for example by means of hot air, the interior of the material is colder than the heating medium.

15 Decomposition of the light-sensitive compound may cause a dense fog, particularly in the case of light-sensitive material in which the light-decomposition product of the light-sensitive compound forms metal nuclei out of the metal salts 20 contained in the material, which nuclei are amplified upon subsequent physical development. An example thereof is a material which is sensitized by means of a solution of a diazonium compound and a mercury salt or a precious metal salt. When heating according to the invention, however, this material does not involve any fog at all.

The photographic material is preferably heated by means of an electric field generated between wire- or rod-shaped electrodes which extend parallel with the surface of the material and in front of which the material is passed in a manner such that the lines of force of the field extend substantially in this direction of motion through the material. If desired, the electrodes may be 35 moved, whereas the material is stationary. With such an electrode arrangement the lines of force extend over a comparatively large distance through the material itself and over a comparatively short distance only through the medium, 40 for example, air between the electrodes and the material. The efficiency of the field is thus enhanced, which is conducive to the compactness of the apparatus.

Though in the case of the electrode arrangement referred to the field strength in the direction of motion of the material is not constant, the results of the treatment in this direction are homogeneous, if only the motion takes place at a constant speed. The homogeneity in a lateral direction of the material is controllable by using electrodes the length of which exceeds the width of the material.

The quantity of gas, for example air, which is passed over the material to carry away any 55 expelled water vapour, is preferably so chosen that

it is exactly sufficient to absorb the evolved water vapour without becoming supersaturated. The excess air may, for example, be 100% or less. This has the advantage that the possibility of dust particles of the air contaminating the photographic material is reduced as much as possible. Use is preferably made of a gas which is pre-heated to approximately 50° C. and is consequently capable of absorbing a large quantity of water vapour.

The invention is of much importance for photographic material in which the quality of the photographic contrast depends upon the moisture content of the material at the moment of exposure. An example of such a material is regenerated cellulose which is sensitized by means of an aqueous solution of a diazonium compound and a mercury salt or a noble metal salt. On exposing such a material, followed by physical development, it is found that the gamma value of the metal image obtained depends upon the moisture content at the moment of exposure (cf. application Serial No. 727,310, filed February 8, 1947, now Patent No. 2,571,671 and application Serial No. 723,426, filed January 21, 1947, now Patent No. 2,571,670). The exposure of such a material, for example for the manufacture of copies of image-and-sound films is preferably effected in a device comprising an apparatus for applying liquid water on to the material, a drying chamber for the adjustment of the degree of humidity of the material, exposure apparatus and means for passing the material through these members in succession (application Serial No. 732,904, filed March 6, 1947, now abandoned). In such a device use may, if desired, be made of unsensitized material, the water and the light-sensitive compound then going into solution therein being applied simultaneously. By effecting the drying operation in such a device in the manner according to the invention, an appreciable simplification of the apparatus is ensured. This is particularly the case if the high-frequency drying operation is effected by means of the aforesaid electrode arrangement. Thus a device is obtained which has practically the same size as a copying device in which the operations preceding the exposure are not effected. Furthermore the said electrode arrangement yields a material having a high degree of homogeneity. This is of importance, since local differences in moisture content give rise to different gamma values. On drying by means of heated air there is a risk of the edge of the material having a different moisture content from that of the central part.

A further very important advantage of high-frequency drying in this case is that, owing to the speed of drying and consequently the speed at which the desired degree of humidity can be adjusted, one and the same film band permits changing over from one degree of humidity to the other in a short time. This may be of importance if, for example, it is desired to copy on one and the same film strip several scenes in succession with different gamma values, for which different moisture contents are consequently required at the moment of exposure. The invention permits changing over from one degree of humidity to the other within a length of 20 cms. of the film.

The invention will be described in connection with the accompanying drawing in which:

Fig. 1 shows one form of apparatus for drying film according to the invention; and

Fig. 2 shows another form of apparatus for

drying film according to the invention. The wet film 1 passes between electrodes 2 of a high-frequency field arranged in a drying chamber 3 provided with an air intake inlet 4 and an air outlet 5. The electrodes are excited by a high frequency generator 6 connected to the electrodes by conductors 7 which are insulated from the walls of the chamber by insulators 8. In Fig. 2, the electrodes 2 of the high frequency drying field are so arranged with respect to the film that the lines of force 9 of the field pass through the film in its direction of motion as indicated by the arrow.

While the invention has thus been described in connection with specific embodiments and applications thereof, other modifications therein will be obvious to those skilled in the art without departing from the spirit and scope of the invention as defined in the appended claims.

What we claim is:

1. A method of drying a photographic film having a thickness of about 40 microns comprising a carrier of regenerated cellulose sensitized with an aqueous solution of a light sensitive diazonium compound and a salt of a noble metal, said photographic film containing at least 1.4 grams of water per cubic centimeter of dry cellulose, comprising the steps of subjecting the photographic film to the action of an electric field of a strength and frequency at which 80 calories per second are generated in the film and capable of expelling more than three-fourths of the initial water content of said film within five seconds, and passing a stream of dry gas over said photographic film during the expulsion of water therefrom to carry the expelled water off as water vapor.

2. A method of drying a photographic film having a thickness of about 40 microns comprising a carrier of regenerated cellulose sensitized with an aqueous solution of a light sensitive diazonium compound and a salt of mercury, said photographic film containing at least 1.4 grams of water per cubic centimeter of dry cellulose, comprising the steps of subjecting the photographic film to the action of an electric field of a strength and frequency at which 80 calories per second are generated in the film and capable of expelling more than three-fourths of the initial water content of said film within five seconds, and passing a stream of dry gas over said photographic film during the expulsion of water therefrom to carry the expelled water off as water vapor.

3. A method of drying a photographic carrier having a thickness of about 40 microns comprising a carrier of regenerated cellulose sensitized with an aqueous solution of a light-sensitive diazonium compound and a salt of a metal lying higher in the electromotive series than copper, said photographic film containing at least 1.4 grams of water per cubic centimeter of dry cellulose, comprising the steps of subjecting the photographic film to the action of an electric field of a strength and frequency at which 80 calories per second are generated in the film and capable of expelling at least 15% by volume of the water in said carrier per second, and passing a stream of dry gas over said photographic film during the expulsion of water therefrom to carry the expelled water off as water vapor.

4. A method of drying a photographic carrier having a thickness of about 40 microns comprising a carrier of regenerated cellulose sensitized with an aqueous solution of a light sensitive diazonium compound and a salt of a metal lying higher in the electromotive series than copper,

said photographic film containing at least 1.4 grams of water per cubic centimeter of dry cellulose, comprising the steps of subjecting the photographic film while in motion to the action of an electric field in which the lines of force of the field extend through the film substantially in the direction of motion of the film, said field having an intensity and frequency at which 80 calories per second are generated in the film and which is capable of expelling at least 15% by volume of water per second in the film, and passing a stream of dry gas over said photographic carrier during the expulsion of water therefrom to carry the expelled water off as water vapor.
